UNITED STATES PATENT OFFICE.

CHARLES E. BERTELS, OF WILKES-BARRÉ, PENNSYLVANIA.

DESIGN FOR A HANDLE FOR WASHBOILERS.

SPECIFICATION forming part of Design No. 24,211, dated April 16, 1895.

Application filed February 14, 1895. Serial No. 538,437. Term of patent 7 years.

To all whom it may concern:

Be it known that I, CHARLES E. BERTELS, a citizen of the United States, residing at Wilkes-Barré, in the county of Luzerne and State of Pennsylvania, have invented a new and original Design for a Handle for Wash-boilers, of which the following is a specification.

This invention relates to a new and original 10 design for handles for wash boilers; and it has for its object to provide a design of this character that shall be both useful and ornamental.

The leading feature or characteristic of the 15 design for a wash boiler handle consists in a U-shaped figure bounded by depending obtuse - angled side portions and a straight transverse portion connecting the upper ends of the side portions of the figure, said straight transverse portions having therein a longitudinal 20 extending concavity, the opposite side edges of the arc of which concavity are disposed in the same plane.

In the drawings:—Figure 1 is a perspective view of a handle for wash boilers embodying the new and original design. Fig. 2 is a vertical sectional view thereof.

Referring to the figures of the drawings, the 25 numeral 1, designates a wash boiler handle shaped to form an inverted U-shaped figure. The U-shaped figure is bounded by opposite

depending side portions 2, and a straight transverse portion connecting the upper ends of the side portions of the figure. As illustrated, the depending side portions 2, of the U-shaped figure are partially twisted to give 35 the same an obtuse angled shape, which disposes the lower extremities of said side portions and the said transverse portion in different vertical planes. The straight transverse portion of the U-shaped figure is provided 40 with a longitudinally extending concavity that makes the straight transverse portion arc-shaped in cross section and the opposite side edges of the arc formed by said longitudinal concavity are disposed in the 45 same plane.

From the above it will be seen that the present invention contemplates a design that is both useful and ornamental.

What I claim is—

The design for a handle for wash boilers herein shown and described.

In testimony that I claim the foregoing as my own I have hereto affixed my signature in the presence of two witnesses.

CHARLES E. BERTELS.
